(57) **CLAIM**

The ornamental design for a measuring cup, as shown, and described.

DESCRIPTION

FIG. 1 is a perspective view of a measuring cup; FIG. 2 is a right elevation view thereof (with the left a mirror image thereof);

FIG. 3 is a front elevation view thereof;

FIG. 4 is a rear elevation view thereof;

FIG. 5 is a top view thereof; and,

FIG. 6 is a bottom view thereof.

The broken lines represent measurement markings, which form no part of the claimed design.
